7 Claims. (Cl. 25—120)

1

This invention relates to a brake for a concrete block molding machine or similar machines. It is the object of the invention to provide a brake which will check the movement of a second set of blocks, as two sets are ejected from the machine before the blocks are lifted off the receiving arms.

This application is a division of my application Serial No. 18,798, entitled Conveyor and Pallet Hoist for Concrete Block Machines, filed April 3, 1948. In that application a system for taking pallets and the blocks from the concrete block machines and depositing them in the drying racks and then returning the pallets to the conveyor and feeding the pallets back into the concrete block machine is described and claimed. One of the chief features of that application is the using of a special host which can take two pallets and blocks at one time off the projecting arms of the machine, deposit two pallets together with the blocks in a drying rack and then electromagnetically pick up two empty pallets from the drying rack and deposit them back on the conveyor. This permits much more rapid operation of the concrete block molding machine and handling of the blocks inasmuch as two pallets are handled each time. One of the difficulties of ejecting two pallets with blocks onto the supporting arms is the liability of the second ejected pallet colliding with the first ejected pallet. To prevent this I have devised a special form of mechanism which properly positions the first ejected pallet at the end of the arms and stops the second pallet before it is projected into contact with the first set of blocks. This will be more particularly described hereinafter.

Referring to the drawings:

Fig. 1 shows part of the concrete block machine together with the projecting arms which support the pallets and blocks when they are ejected from the machine.

Fig. 2 is a cross section taken on the line 2—2 of Fig. 1.

Fig. 3 is an enlarged view looking at the inside of one of the work supporting arms and showing my braking mechanism before it is activated to effect braking action.

Fig. 4 is a similar view showing the first pallet and blocks ejected from the machine and the braking mechanism in position to check the second set of blocks and pallet.

Fig. 5 is a plan view of the two work supporting arms showing in dotted lines the first pallet and set of blocks ejected from the machine.

2

Fig. 6 is a section taken on the line 6—6 of Fig. 3.

Fig. 7 is a detail of the arm supporting stanchion of the machine showing how the bolt receiving recess is provided with clearance to permit considerable adjustment of the arms for the purpose of altering the angle of the runway or arms as shown by comparing the full line with the dotted line showing of Fig. 1.

10 1 designates the concrete block molding machine which is more particularly described in the aforementioned parent application. Suffice it to say here that 2 is a mold which is shown in Fig. 1, stripped from the finished concrete block 3 which rests on a pallet 4 which is ejected from the concrete block machine by means of a pusher 5 which is an angle bar 6 connected with the reciprocating bars 7, which in turn is operated by bar 8 and connecting rod 9. As the connecting rod pushes 20 the bar 8 forward the links 10 raise the cross bar 5 and it engages the pallet 4 and pushes the pallet out onto the runway which comprises a pair of work supporting arms 11 and 12. These arms support the studs 13 on which turn the rollers 14. The pallet, when pushed by the pusher 5 rides forward on the rollers 14 of the runway and the first pallet and set of blocks will be stopped by the pallet stopper 15 which is adjustable in elevation by means of the slot and screw arrangement 16.

30 The braking apparatus comprises the pivoted arm 17 which has the shoe 18. It will be seen that the shoe 18 is slightly elevated above the level of the rolls in Fig. 3, and this is the normal position due to gravity. The rear braking shoe 19 and its appurtenances have a greater moment than the left hand arm 18a and the shoe 18. Consequently the shoe 18 will naturally be elevated. When the first pallet with the set of blocks, usually three, is thrust out of the machine by the pusher 5, this pallet strikes the elevated shoe 18, depresses it and throws up the braking lever 18a and the shoe 19. The braking shoe 19 is also pressed upwardly by means of the coil springs 20. It will be seen that the now inclined shoe is directly in the path of the second pallet and set of blocks and this forms a very effective brake of the movement of the second pallet and the second set of blocks and is arranged so as to stop the second pallet before there is a collision with the first pallet.

40 45 50 55 The proper timing in stopping the pallets and the blocks can be achieved by adjusting the work supporting arms 11 and 12. The more the inclination of the arms, the faster the blocks will

ride out of the machine on the rollers; compare the full line showing with the dotted line showing—this dotted line showing is of course an extreme position. The work receiver arms 11 and 12 are connected by a cross bar 22. This connects the arms with the stanchions 21. The bolt 23 forms a fulcrum on which the cross member 22, together with the work supporting arms 11 and 12 can be tilted when the screw bolt 24 is released from the block 25. There is one block on each end of the cross member 22. By releasing the bolt 24 and by reason of the amount of clearance 26 (see Fig. 7) that there is around this screw bolt, it is possible to vary the inclination of the arms as is shown in Fig. 15. This is desirable in order to give just the proper movement to the blocks as they are ejected from the machine and coordinate the movement of the blocks with the braking effort. For instance, in cold weather when the lubricant is somewhat congealed, it will be necessary to adjust the arms for greater declination because the rollers will not turn so easily. In hot weather when the grease or oil on the rollers is thin, it will be necessary to raise the arms some to cut down the rate of movement of the pallets and the sets of blocks.

However, with this arrangement in conjunction with the pusher of the concrete block molding machine, the second set of blocks with its supporting pallet is slowed up by the braking action and will not collide with the first set of blocks, hence the machine may manufacture two sets of blocks before the blocks are removed. These blocks, as already stated, are removed by a hoist that has outstanding arms that pass under the two pallets and lifts the pallets with their load off the arms and places the pallets with the finished blocks in a drying rack that is described more thoroughly in the parent application.

What I claim is:

1. A runway in combination with a concrete block machine having a reciprocating pusher comprising a pair of arms projecting outwardly from the machine and arranged to form a track or guide for pallets pushed out of the machine and arranged to receive the pallets and braking means on the said arms for automatically braking the movement of a pallet pushed out of the machine to prevent it overthrowing beyond its proper position upon the runway.

2. A runway in combination with a concrete block machine having a reciprocating pusher comprising a pair of arms projecting outwardly from the machine and arranged to form a track or guide for pallets pushed out of the machine and arranged to hold a plurality of pallets and braking means on the said arms for automatically braking the movement of the second loaded pallet pushed out of the machine to prevent it

from colliding with the first pallet pushed out of the machine, the said braking means comprising one or more levers secured to the arms and having front ends depressed by the first ejected pallet to cause the rear end of the lever, which has a braking shoe, to rise to braking position in the path of the second loaded pallet coming out of the machine.

3. The combination claimed in claim 2 in which the pair of arms carries a plurality of rollers on which the pallets roll to their positions of rest on the runway.

4. The combination claimed in claim 2 in which the arms are adjustable to alter the inclination of the runway to coordinate the movement of the pallets and the blocks with the braking means.

5. The combination claimed in claim 2 in which the lever has a shoe at the forward end to be contacted by the first pallet to throw up the rear end of the lever and a shoe at the rear end to contact and brake the movement of the second pallet ejected from the machine.

6. The combination claimed in claim 2 in which the brake lever has a contact shoe at the forward end which is normally in the path of the first pallet and set of blocks by reason of the lever being overbalanced and in which there is a braking shoe at the rear end which is projected up into the path of the second pallet when the first shoe is depressed by contact with the first pallet.

7. The combination claimed in claim 2 in which the lever comprises a contact shoe at the forward end which is normally in the path of the first pallet by reason of the overbalance of the lever, and a braking shoe at the rear end projected upwardly by one or more springs and which shoe forms a spring activated brake or drag on the second pallet ejected from the machine when the front end of the lever is overbalanced by the force of the first pallet and its blocks.
